UNITED STATES PATENT OFFICE.

JAMES DIXON, OF NEW YORK, N. Y., ASSIGNOR TO HENRY BREWSTER, JOHN W. BRITTON, CHANNING M. BRITTON, AND CHARLES J. RICHTER, OF SAME PLACE.

VEHICLE-BODY.

SPECIFICATION forming part of Letters Patent No. 340,297, dated April 20, 1886.

Application filed February 10, 1886. Serial No. 191,489. (No model.)

To all whom it may concern:

Be it known that I, JAMES DIXON, of the city and county of New York, in the State of New York, have invented a new and useful 5 Improvement in Vehicle-Bodies, of which the following is a specification.

My invention relates to vehicle-bodies in which the sides and ends are connected or joined by square or angular corners, as is usual where the side and end are two separate pieces united by a miter or butt joint. It has been proposed to form the side and end of a body of one continuous piece bent so as to form a curved or rounded corner, 15 but such curved or rounded corners are not desirable in a vehicle-body; and the object of my invention is to provide a vehicle-body the corners of which are square or angular, so as to present the appearance of a body in 20 which the sides and ends are united by joints, and which will be stronger at the corners than is a body having joints at the corners.

The invention consists in a vehicle-body having its sides and ends composed of portions which are bent to form square or angular corners, and which are joined together between the corners, as distinguished from a body having the pieces which form its sides and ends bent to form curved or rounded corners. 25

In the accompanying drawings, Figure 1 represents a perspective view of a vehicle-body embodying my invention; and Fig. 2 is a horizontal section thereof, showing more 35 clearly the two portions or sections of which the sides and ends of the body are composed and the joints which connect the two sections or portions at the opposite ends of the body.

Similar letters of reference designate corresponding parts in both figures.

In the example of my invention shown the sides and ends of the body are composed of only two separate portions or sections, A A, 45 each of which is of a length to form one entire side and half of each end. The two portions A A are bent squarely at the points a, to form the square or angular corners of the body, and the ends of the two portions or 50 sections A are joined together at the ends of the body by a long scarf-joint, b, or by any other suitable joint.

In order to strengthen and sustain the cor-

ners, they may be filled in with the usual corner pieces or blocks, c, and may have corner 55 irons, d, applied in the usual way. At the bottom of the sides and ends of the body I have represented the usual wooden rockers or bottom sides, e.

It will be seen that by my invention I provide 60 a vehicle-body which has only two joints in the sides and ends, and in which the corners are solid, or have the portions extending from them formed of a single piece of material. Not only is this construction advantageous, 65 because there are only two joints, b, but it is still further very desirable because these joints, being in the straight portions of the body—in the end, for example—are so located that long scarf joints or other joints may be 70 formed which will not be liable to open or separate.

The portions A A are made of elm or other wood which is susceptible of being bent when properly steamed or treated. 75

I am aware that a vehicle-body having rounded or arc-shaped corners has been made of portions which are bent to form such rounded corners; but such a vehicle-body is objectionable, because its corners are not 80 square or angular, and are readily distinguishable from the jointed corners, which are square or angular. By experiment I have found that by employing a proper quality of wood and properly steaming or softening it, 85 the corners may be bent squarely or angularly and made to simulate the ordinary body, in which the sides and ends are joined by a miter or butt joint to form a square or angular corner. I do not therefore desire to 90 include in my invention a body of the kind above described as old.

What I claim as my invention, and desire to secure by Letters Patent, is—

The vehicle-body herein described, having 95 its sides and ends composed of portions which are bent squarely, so as to form square or angular corners, and are joined between the corners, as distinguished from a body in which the pieces constituting the sides and ends 100 are bent to form curved or rounded corners, substantially as and for the purpose herein set forth.
